UNITED STATES PATENT OFFICE.

DANIEL ASHWORTH, OF KENTON COUNTY, KENTUCKY.

DESIGN FOR A LAMP.

Specification forming part of Design No. 6,385, dated February 11, 1873

To all whom it may concern:

Be it known that I, DANIEL ASHWORTH, of county of Kenton and State of Kentucky, have invented certain new and useful Improvements in Designs for Lamps, of which the following is a specification:

The nature of my invention relates to the improvement in the appearance of lamps; and consists in an ornamental design for the bowl and in the conformation of the foot and standard so as to reflect the light, as will hereafter be more fully set forth.

The accompanying photographic illustration represents my invention.

a represents the bowl of the lamp, upon the side of which there is formed one or more ears of corn, standing among or surrounded by a number of blades of corn or other suitable devices. This ear may be placed in the position shown, or in any other that may be preferred. Just above this ear, running entirely around the bowl, so as to form a band, are a number of small vertical ridges, b, over which the upper portion of the bowl projects. The foot and standard of the lamp is hollow, of the conformation shown, the standard having eight sides, and the foot ten, which reflect the light in such a manner that the foot looks as if it were cut instead of pressed.

This design is very pretty, neat, and tasty, and adds greatly to the beauty of the lamp.

Having thus described my invention, what I claim as new, and desire to secure by Letters Patent, is—

The design for a lamp consisting of the ear of corn, the band around the bowl, and the standard with eight and the foot with ten sides, substantially as set forth.

In testimony that I claim the foregoing as my invention I hereunto affix my signature this 9th day of January, 1873.

DANIEL ASHWORTH.
